UNITED STATES PATENT OFFICE.

FREDERICK OERTLY, OF PHILADELPHIA, PENNSYLVANIA, ASSIGNOR TO JOHN BROMLEY & SONS.

DESIGN FOR A CARPET.

Specification forming part of Design No. 11,263, dated June 24, 1879; application filed May 17, 1879.
[Term of patent 3½ years.]

To all whom it may concern:

Be it known that I, FREDERICK OERTLY, of Philadelphia, Pennsylvania, have invented a new and Improved Carpet Design.

To enable those skilled in the art to make and use my improved design for carpets, reference is made to the accompanying photographic illustration, which is a correct delineation thereof.

What I claim as new, and desire to secure by Letters Patent, is—
The design for carpets, as shown.

FRED. OERTLY.
